UNITED STATES PATENT OFFICE.

GARFIELD PERRY SMITH, OF PROVINCETOWN, MASSACHUSETTS.

INDICATOR FOR SUBMARINE VESSELS.

1,120,417.

Specification of Letters Patent.

Patented Dec. 8, 1914.

Application filed January 14, 1914. Serial No. 812,123.

To all whom it may concern:

Be it known that I, GARFIELD PERRY SMITH, a citizen of the United States, and a resident of Provincetown, in the county of Barnstable and State of Massachusetts, have invented a certain new and useful Improved Indicator for Submarine Vessels, of which the following is a specification.

The object of the invention is to provide an automobile torpedo, torpedo dummy, submarine or other vessel adapted to travel beneath the surface of the water, with means for indicating its course through, or its final resting place beneath the water to thereby enable persons on surface vessels, or on shore, to see the direction the vessel has taken after being launched, and also to locate its final resting place either, after the motive power or projecting force has been spent or in the event of the vessel being arrested in its course and held below the surface of the water.

The means employed is oil, and the invention consists in arranging an oil reservoir within the chamber at the after end of the torpedo, torpedo dummy or other vessel, which opens through the skin of the torpedo or other vessel so that, when the latter is launched, the reservoir will be open to the surrounding body of water which permits water to enter the reservoir and float the oil therefrom, and since the oil is of less specific gravity than the water, it will float so and spread upon the surface, either in a stream-like film or in small patches thus leaving a trail on the surface by which those on surface vessels may readily observe the course the torpedo or vessel has taken or the proximity of its final resting place. The invention further consists in certain details of construction as will be hereinafter described and then claimed.

In the drawings illustrating the invention, in the several figures of which like parts are similarly designated, Figure 1 is a side elevation of an automobile torpedo, the latter being partly broken away to illustrate the location of my invention. Fig. 2 is a transverse section on a larger scale, drawn on the line a—a of Fig. 1. Fig. 3 is a detail longitudinal section of a portion of the after end of the torpedo illustrating a slightly different arrangement of the outlet from the oil reservoir. Fig. 4 is a transverse section of a torpedo illustrating a further modification of the invention.

1 designates an automobile torpedo of standard design in the chamber 1', at the after end of which, is located an oil reservoir 2, which, in the preferred construction as shown in Figs. 1 and 2, is provided in its top with an outlet 3 which opens through the skin of the torpedo and with a water inlet 4 that extends from the top of the torpedo to the bottom of the reservoir 1. The reservoir may be held in position within the chamber 1' in any suitable manner and for the purpose of illustration I show it supported upon a bar or plate 5 held to the skin of the torpedo.

In Fig. 3, I illustrate a slightly different construction of the invention in which the reservoir 6 is shown provided with a collar 6' extending from its top and having a flanged upper end which is connected air-tight and water-tight to the skin of the torpedo. The top of the reservoir is provided with a single opening 7 that is controlled by a flap-valve 8, said valve having an upwardly extending wing 9 which projects above the periphery of the torpedo so that when the torpedo is launched and is traveling through the water, the water will strike against the wing 9 and unseat the valve 8 to thereby permit water to enter the reservoir and the oil to gradually float therefrom. This arrangement of valve provides a cover for the outlet and prevents evaporation of the oil when the vessel is lying idle and in practice the wing is made slightly heavier than the valve proper so that when the water strikes against the wing it will be thrown back and by its weight drop against the top of the reservoir as shown in dotted lines to thus permanently hold the valve from its seat when the torpedo comes to rest.

In Fig. 4, I show still another arrangement of the reservoir, in which the latter 11 is provided with an outlet pipe 12 extending from the top of the reservoir 100 through the top of the vessel, and with a water inlet pipe 13 extending from the bottom of the reservoir and opening through the bottom of the vessel. The pipe 13 is provided with a flap-valve 14 which is held to its seat before the vessel is launched by the oil in the reservoir and which will be floated and unseated by the water when the vessel is launched to thereby permit the water from the surrounding body of water 110 in which the vessel is operating to leak into the reservoir to thus float the oil therefrom.

As is well known to those having experience in launching automobile torpedoes or dummy torpedoes, either in actual warfare or in target practice, that owing to various causes, such as rough seas or faulty steering gear, they often deviate from their course, and with automobile torpedoes while they run very accurately at high speeds, at low speeds they are uncontrollable and erratic, and often through fault in the functioning of the horizontal rudder they plunge toward and embed their nose into the bottom into which they stick, and, in consequence are lost, and unless they do sink to the bottom, they are dangerous to navigation since they usually float immediately below the surface. With the use of my attachment, however, after the torpedo or dummy strikes the water the water will enter the reservoir and float the oil to the surface, which owing to its specific gravity, will immediately rise to and spread upon the water's surface in small patches thus indicating to those in surface vessel the course the torpedo or dummy has taken, and in the event of its plunging into the bottom, or when its momentum is lost, the oil will continue to escape from the reservoir and form a large oily surface in the immediate vicinity of its resting place to thereby indicate its locality and consequently to facilitate its recovery.

While I have shown and described my attachment for use in connection with automobile torpedoes or dummy torpedoes, I do not wish to be understood as confining myself to these uses as it will be understood that the attachment may be used with equal effectiveness on submarine boats especially when they are used in submerged trial runs or when operating in connection with a parent surface vessel or a fleet. Especially would my attachment be serviceable on submarine vessels when operating with a fleet of surface vessels in rough weather since, in very rough weather, the submarines may be operated submerged and caused to travel in advance of the surface fleet and by emitting the oil from the reservoirs they not only provide a means for indicating to those on board the surface vessels, their approximate locality and the course they are running, but also the additional purpose of spreading oil upon the troubled waters to smooth the surfaces and thus facilitate the progress of the surface vessels.

I am aware that mechanical devices have been employed in connection with automobile torpedoes and dummy torpedoes for giving them positive buoyancy and causing

them to rise to the surface in the event of their sinking below a certain depth through faulty action of their horizontal rudders or other mechanically operated parts, but these devices are expensive and owing to their location are ineffective especially should the torpedo or dummy take a downward course and stick its nose into the bottom of the water-bed, and I make no claim to a device for regulating the buoyancy of the vessel or for causing it to float upon the surface after its propelling mechanism or its initial propulsive force has been spent, but

What I do claim and desire to secure by Letters Patent is,

1. The combination with a vessel adapted to travel beneath the surface of the water and having a chamber therein, and of means carried within the said chamber and adapted to escape therefrom for indicating the course or final resting place of the said vessel below the surface of the water.

2. An attachment for vessels adapted to travel beneath the surface of the water, comprising an oil reservoir arranged within the vessel and open to the surrounding body of water, whereby to permit water to enter said reservoir and the oil to be floated therefrom when the vessel is submerged, substantially as specified.

3. An attachment for automobile or dummy torpedoes, comprising an oil reservoir arranged within the vessel, and oil outlet extending therefrom and opening into the surrounding body of water, and a water inlet leading to said reservoir from the surrounding body of water.

4. An attachment for vessels adapted to travel beneath the surface of the water, comprising an oil reservoir arranged within the vessel, and a valve-controlled outlet leading from said reservoir and opening through the skin of the vessel.

5. An attachment for vessels adapted to travel beneath the surface of the water and having a chamber at its after end, comprising an oil holding reservoir, an outlet therefrom leading to the exterior of the vessel, and a valve controlled inlet leading from the surrounding body of water in which the vessel is operating to said reservoir.

In testimony whereof I have hereunto set my hand this 12th day of January, A. D. 1914.

GARFIELD PERRY SMITH.
